(57) **CLAIM**

The ornamental design for a dosimeter badge, as shown and described.

DESCRIPTION

FIG. 1 is a front view of one embodiment of the dosimeter badge of the present invention;

FIG. 2 is a right-side elevational view of the dosimeter badge thereof, the left-side elevational view being identical thereto;

FIG. 3 is a front elevational view of the dosimeter badge thereof; the rear elevational view being identical thereto;

FIG. 4 is a rear view of the dosimeter badge thereof;

FIG. 5 is a front view of a second embodiment of the dosimeter badge of the present invention, the remaining views being the same as set forth in FIGS. 2-4;

FIG. 6 is a front view of a third embodiment of the dosimeter badge of the present invention, the remaining views being the same as set forth in FIGS. 2-4;

FIG. 7 is a front view of a fourth embodiment of the dosimeter badge of the present invention, the remaining views being the same as set forth in FIGS. 2-4;

FIG. 8 is a front view of a fifth embodiment of the dosimeter badge of the present invention, the remaining views being the same as set forth in FIGS. 2-4; and

FIG. 9 is a front view of a sixth embodiment of the dosimeter badge of the present invention, the remaining views being the same as set forth in FIGS. 2-4.

FIG. 10 is a front view of a seventh embodiment of the dosimeter badge of the present invention, the remaining views being the same as set forth in FIGS. 2-4; and,

FIG. 11 is a front view of a eighth embodiment of the dosimeter badge of the present invention, the remaining views being the same as set forth in FIGS. 2-4.

The broken lines, including those forming the numerals and text, have been shown for illustrative purposes only and form no part of the claimed design. Shading has been shown to represent that portions of the claimed design have different colors.

1 Claim, 10 Drawing Sheets
